UNITED STATES PATENT OFFICE.

GEORGE E. ADAMS, OF NEW BRITAIN, CONNECTICUT.

DESIGN FOR A BODY PORTION OF GARMENT-SUPPORTER LOOPS.

SPECIFICATION forming part of Design No. 32,207, dated February 6, 1900.

Application filed December 23, 1899. Serial No. 741,478. Term of patent 7 years.

To all whom it may concern:

Be it known that I, GEORGE E. ADAMS, a citizen of the United States, and a resident of New Britain, in the county of Hartford and State of Connecticut, have invented and produced a new and original Design for the Body Portion of Garment-Supporter Loops, of which the following is a specification, reference being had to the accompanying drawings, forming a part thereof.

In the drawings, Figure 1 is a front, and Fig. 2 an end, elevation of the body portion of a loop embodying the present design.

The leading and characteristic features of the present design are the substantially straight section of the bottom bar at A and the shorter straight section B at the top of the loop, with the intermediate outwardly-bowed portions C. The outwardly-bowed portions C extend inwardly farther at the top

than at the bottom and are connected with the straight portion B by upwardly-extending portions D. The lower portion of said bows are connected with the straight portion of the bottom bar A by short downwardly and inwardly extending portions E. The design of the body portion of the loop illustrated is symmetrical, each half taken on a vertical line being a duplicate of the opposite half, and each half presents the peculiar sharp outwardly bowed or looped portion C before referred to.

What I claim is—

The design for the body portion of a garment-supporter loop as herein shown and described.

GEORGE E. ADAMS.
